ELECTRICAL CONTACT SPRING ASSEMBLY

Sten Daniel Vigren, Stockholm, Walter Otto Wilhelm Broberg, Nynashamn, and Rolf Albin Zander, Stockholm, Sweden

Application April 14, 1952, Serial No. 282,112

7 Claims. (Cl. 200—166)

This invention relates to contact-spring assemblies for electric switching devices having both stationary and movable contact springs and wherein the movable contact-springs are operated under the control of a unitary stud common to all of the movable springs of the assembly.

In designing a contact-spring assembly of this type it is desirable to minimize the number of different component parts included in the assembly and to so arrange the assembly that all contact-functions required can be performed by these parts. Thus the insulating plates between the springs should be interchangeable, the number of different types of contact-springs should be limited, the thickness of the springs should be the same for all contact-springs and all contact-springs should be provided with the same type of contacts. Furthermore, the operating-stud should be designed so as to be adaptable to any desired contact-functions. The mode of operation of the contact-functions should be uniform, and the counter-pressure upon completed closing-operation should be independent of the position of the operating-stud.

In some known types of contact-spring assemblies, the contact-functions, which are intended to perform closing-operations on the upward movement of the operating-stud are arranged in such a way that the stationary contact-spring resting on the upper surface of a tooth of the supporting-stud will determine the contact-pressure when the closing-operation is completed. On completing the closing-operation, the stationary contact-spring has to be lifted a small distance above the tooth in order to ensure an efficient contact, and for this reason the groove adjacent to the tooth has a width considerably greater than the thickness of the contact-spring.

It has been found that, when the contacts of the movable contact-spring strike against the contacts of the stationary contact-spring, the latter will bounce upwards and disengage its contacts from the contacts of the movable contact-spring. There is nothing that prevents the fixed contact-spring from bouncing since, as already mentioned, the latter has to be somewhat movable and resilient in order to produce the desired contact pressure. These bounces, which are repeated several times during a closing-operation cause sparks and destroy the contacts.

In contact-functions which are break-operations on the upward movement of the operating-stud, the movable contact-spring causes the contact-pressure by resting with its contacts upon the contacts of the stationary contact-spring. The stationary contact-spring rests upon the upper surface of a tooth of the supporting-stud. At the break-operation, the movable contact-spring is lifted upwards, by the upward movement of the operating-stud, by a tooth of the operating-stud. When a break-contact is in a non-operated condition there is a small air-gap between its movable contact-spring and that tooth of the operating-stud which is intended to actuate the movable contact-spring. This small air-gap will ensure that the movable contact-spring, while abutting with its contacts against the contacts of the stationary contact-spring, does not touch the tooth of the operating-stud.

2

On the downward movement of the operating-stud, the contacts of the break-contact will be closed again, i. e., the break-contact acts as a make-contact.

Thus on closure of the break-contact, the movable contact-spring effects the contact-pressure and the fixed contact-spring will have a fixed position since it abuts with pressure against the upper surface of a tooth of the supporting-stud.

Although in this case the stationary contact-spring is prevented from bouncing through its abutment against the associated tooth of the supporting-stud it will be understood, that this manner of contact closure generally shows a much less tendency to bounce than is the case in the manner of contact closure used in the described make-contacts.

In the make-contacts the movable contact-spring is forced towards the stationary spring by the operating-stud and the force with which it strikes the stationary spring is largely due to the kinetic energy of the entire armature system. Since in a break-contact the movable spring is tensioned so as to perform its contact closure movement by its own spring tension and the task of the operating-stud is merely to release the movable spring so as to move against the cooperating stationary spring, the force with which the movable spring hits the latter is merely determined by the relatively small spring-tension and weight of the movable spring.

This is the main and basic reason why in known devices the contact-closures of break-contacts are generally more free from vibration than the contact-closures of make-contacts.

It is an object of this invention to provide contact-spring assemblies, which may be composed of different optional contact units or combinations by means of a small number of different basic elements comprising stationary and movable contact-springs and an operating-stud having teeth, shoulders or the like for the operation of the movable springs, in which not only the break-contacts but also the make-contacts are arranged to give a contact-closure substantially free from vibration according to the "release" principle outlined above.

The invention is foremost characterised by the fact, that said teeth, shoulders or the like of the operating-stud form pairs of opposing abutting-surfaces for each pair of neighboring contact-springs, the pairs of contacts-springs being disposed with even spacing, and that the movable contact-springs forming part of make-contacts as well as break-contacts co-operate with abutting-surfaces of the operating-stud that are directed from the respective associated stationary contact-springs and are tensioned so as to tend to move towards the respective associated fixed contact-springs under their spring-tension.

The following is a description, by way of example, of contact-spring assemblies according to the present invention, reference being made to the accompanying drawings, wherein:

Figure 1 shows a contact spring assembly according to the invention in side elevation.

Figure 2 shows the same contact spring assembly in end elevation.

Figure 3 shows the same contact spring assembly as seen in plan.

Figure 4 shows the same contact spring assembly in cross section along line A—A in Figure 1.

Figure 5 shows part of the contact spring assembly according to Figure 1 with the difference that the two lowest springs have been inter-changed.

Figure 6 shows the same contact spring assembly as Figure 1 except that the operating-stud is disposed transversally and has two teeth for each movable contact spring.

Figure 7 shows the last-mentioned contact spring assembly in end elevation.

Figure 8 shows one of the fixed contact springs used in the embodiments illustrated in plan view.

Figure 9 shows one of the movable contact springs in plan view.

The contact spring assembly shown in Figure 1 is built up of seven contact springs on a fixed supporting bridge 1 on which a guiding plate 2 rests. The guiding plate 2 guides the lower portion of a vertically movable operating stud 3 and a fixed supporting stud 4. Plates 5 insulate the contact springs from each other. Contact springs 6, 7 and 8 are stationary members fitted into narrow grooves on the supporting stud 4, while contact springs 9-12 are movable springs controlled by the operating stud 3. The upper portions of the operating stud 3 and the supporting stud 4 are guided by a combined pressure and guiding spring 13. The whole spring assembly is held together by a screw 14.

The operating stud 3 and the supporting stud 4 are pressed against the guiding plate 2 by the combined pressure and guiding spring 13. Since the pressure and guiding spring 13 is formed with two tongues, a relatively fixed inner tongue to act upon the supporting stud 4 and a movable outer tongue to act upon the operating stud 3, the operating stud may be actuated by a lifting member without appreciably affecting the pressure on the supporting stud.

The contact spring assembly illustrated in Figure 1 comprises three contact groups for performing three different contact functions. The particular one of the contact functions depends on the function which the contact springs with their contacts will perform on the upward movement of the operating stud 3. It is evident that when the lifting stud after completion of its upward movement moves downwards again, the functions of the contact springs will be reversed.

The contact function of the lowest contact spring assembly shown in Figure 1 is a break contact. When the operating stud 3 is in non-operated position there is a small air gap between the upper surface of the movable tooth 15 and the corresponding movable contact spring 12. This small air gap is necessary for the sake of contact efficiency, because it must be ensured that the contact spring does not abut against the upper surface of the tooth 15, since otherwise there would be a risk that the pressure of the contact spring 12 would be entirely or partially absorbed by the surface of the tooth 15 and not by the contacts of contact spring 6. When the operating stud 3 is operated by a lifting member, for instance an armature, and stud 3 moves upwards, the upper surface of the tooth 15 will first pass through the small air gap between the tooth 15 and the free end of movable contact spring 12 whereupon the tooth during its upward movement will move this contact spring 12 and separate its contacts from the contacts of the relatively stationary contact member 6. In other words a break is effected in the electrical connection between contact springs 6 and 12.

The middle spring group contact function in the contact spring assembly shown in Figure 1 is a make contact. As long as the operating stud is in its lower, or non-operated position the underneath side of the tooth 16 holds the movable contact spring 11 in such a position that an air gap exists between the contacts of this relatively movable spring 11 and the contacts of the fixed spring 7. The movable contact spring 11 abuts against the underneath side of the tooth 16 with a pressure at least as great as the contact pressure which it is intended to exert. When the operating stud moves upwards under control of the lifting member, the movable contact spring 11, the pressure of which is directed in the direction of movement of the operating stud, follows the underneath side of the tooth 16. The movement of the movable contact spring 11 will continue until its contacts have passed

the space that initially separates them from the contacts of the fixed contact spring 7. When the contacts of the movable contact spring touch the contacts of the stationary contact member 7, the movement of the movable contact spring 11 will cease, while the movement of the actuating stud continues until a small space has been formed between the underneath side of the tooth 16 and the movable contact spring 11. This space assures the maintenance of desired contact pressure in the same manner as described above in connection with the break contact.

The contact function of the uppermost contact group in the contact spring assembly shown in Figure 1 is a break-before-make contact. The number of springs comprised in a break-before-make contact is at least three as shown in Figure 1 and includes in this case a fixed contact member 8 having contacts on both sides and two movable contact springs 9 and 10 located one on each side of the fixed contact member 8. The contact member 8 forms together with the lower movable contact spring 10 a make contact and with the upper movable contact spring a break contact. When operating as a break-before-make contact, the lower movable contact spring 10 strikes with its contacts against the contacts of the fixed contact member 8 after the upper movable contact spring 9 has broken the contact with the fixed contact spring.

The mode of operation of the functions of the break-before-make contact is analogous to the break and make functions described above.

A break-before-make contact can be altered to a make-before-break contact in the following manner:

That portion of the lower movable contact spring 10 which is positioned between its contacts and the operating stud 3 is bent downwards. Then the contacts of the lower movable contact spring will be brought nearer to the contacts of the fixed contact spring. The closure will thus occur within a shorter time. The corresponding portion of the upper movable contact spring 9 is preferably bent upwards. The space between the upper surface of a tooth 17 of the operating stud 3 and the upper movable contact spring 9 is then increased. During the upward movement of the operating stud, the tooth will reach the upper contact spring 9 later and consequently the break will also occur later. The adjustment should be carried out so that the make occurs before the break. When thus operating as a make-before-break, the lower movable contact spring 10 hits with its contacts against the contacts of the fixed contact member 8 before the upper movable contact spring 9 breaks the contact with the fixed contact member 8.

A make-before-break operation may also be obtained by increasing the height of the contacts of the fixed contact member 8. The spacing between the contacts of the make contact will then decrease, and the make will occur earlier while the break will occur later, because the distance between the upper side of the tooth 17 and the movable contact spring 9 has increased due to the increase in height of the contacts on the fixed contact spring.

When the lifting member is restored, the operating stud returns to its initial position substantially through the action of the outer tongue of the pressure and guiding spring 13, which yieldingly urges the operating stud towards the guiding plate 2. The operation of the contact groups is then reversed, the lower contact group acting as a make contact, the middle contact group as a break contact and the upper contact group as a make-before-break contact with the make at the top and the break at the bottom.

When contact closures accompany the upward movement of the operating stud, the upper side of a tooth does not lift the movable contact springs 10 and 11, but the movable contact springs press, due to their tension, against the underneath side of the tooth and follow, due to the said tension, the stud upwards until they are stopped by the contacts of the fixed contact springs. A

similar operation will occur with regard to the break contacts when the stud moves downwards and the break contacts are closed, the movable contact springs of the break contacts then following instead the upper side of the tooth. Thus after the closure is completed the contact pressure will be independent of the continued movement and position of the operating stud.

Figure 5 shows a modification of the lowermost contact spring group assembly according to Figure 1. The movable contact spring 12 has changed position with the fixed contact spring 6 and forms together with the latter a make contact instead of a break contact as in Figure 1. In Figure 5 the movable contact spring abuts against the underneath side of the tooth 15. As will be understood from the above, the movable contact spring will be guided on its upward movement by the upper side of a tooth if the contact function is a break. If the contact function is a make, the movable contact spring will be guided by the underneath side of the tooth. As will further appear from the figure, a break contact will become a make contact and vice versa if the contact springs in a contact function are interchanged and the movable contact springs of the contact function are guided by the same tooth. This guiding action is achieved by a displacement of the teeth of the operating stud in relation to those of the supporting stud.

Figures 6 and 7 show a contact spring assembly similar to that of Figure 1 having fixed contact members 6-8 and movable contact springs 9-12. A modified operating stud 18, however, has been substituted for the operating stud 3. The stud 3 in Figure 1 has its teeth turned inwards to the spring assembly, one tooth controlling both the contact-carrying tongues of each movable contact spring. The operating stud 18 shown in Figures 6 and 7 is provided with two teeth for each movable contact spring and is inserted between the contact-carrying tongues of the movable contact springs 9-12 and is positioned so that the two tongues of each movable contact spring will each be controlled by an individual stud tooth. Then the spacings between the movable contact springs and the teeth of the operating stud can be viewed more conveniently from the front end of the spring assembly. In the contact spring assembly according to Figures 1 and 6 there are provided teeth, both on the operating stud and on the supporting stud for all possible arrangements of movable contact springs and stationary contact members within the contact spring assembly.

In the arrangement shown in Figs. 6 and 7, it may be desirable to provide the supporting stud 4 with pairs of laterally extending teeth like operating stud 18 in order to obtain a better support for the fixed contact members.

The regular relation between make and break functions is made possible by a displacement of the teeth of the operating stud with respect to the teeth of the supporting stud.

In the design of the operating and supporting studs, the spacings between the teeth of the studs must agree with the spacing between the contact springs or the contact functions in the contact spring assembly. It is not possible to arrange the operating and supporting studs so that the upper sides of their teeth are on a level with each other. In Figure 8 a fixed contact spring is shown having a slot 35 at the contact end, in which the supporting stud fits, and a twin contact with two contacts 36. In Figure 9 a movable contact spring is shown having a slot 37 through which the supporting stud may pass without actuating the spring.

In the embodiments described above all contact operations, makes as well as breaks, have been performed in accordance with the principle that the respective movable contact spring effects the closure of contacts by movement due to its own spring tension irrespective of whether the contact closure occurs on the operation or release of the relay.

We claim:

1. A contact spring assembly comprising a base member, spaced generally parallel stationary contact members and movable contact springs for circuit making and breaking cooperation with each other disposed in at least one group, fixing means for fixing one end of each of said movable contact springs with relation to said base member on any of a number of predetermined, substantially evenly spaced levels above said base member so as to hold the movable contact springs in piled-up relation on the same and leave the other end of each movable contact spring free to move in a direction substantially perpendicular to the longitudinal direction of the movable contact springs, said fixing means comprising means for holding each of said stationary contact members on any of a number of predetermined levels, not occupied by movable contact springs, which levels substantially coincide with said first-mentioned levels, and in engageable relation with said movable contact springs, each of said contact springs being pre-tensioned so as to tend to flex its free end into engagement with its cooperating stationary contact member and being situated on one side of its cooperating stationary contact member when forming part of a make contact group and on the other, opposite side of its associated stationary contact member when forming part of a break contact group, the contact spring assembly further comprising an operating, comb-like stud member, means for movably supporting the operating stud member at the free ends of the movable contact springs to be slidable between a non-operated and an operated position, the direction of said sliding being substantially perpendicular to the longitudinal axis of the movable contact springs, said operating stud member having evenly spaced teeth thereon for engaging the free ends of said movable contact springs, a tooth adapted for the individual actuation of a single movable contact spring being provided substantially in alignment with each of the spaces between said first-mentioned levels at least one of said teeth controlling a make contact group and at least one other of said teeth controlling a break contact group, and each tooth defining two opposed surfaces extending substantially normally to the direction of said sliding, that surface of each tooth controlling a make contact group which is turned against the direction of said sliding on operation of the said stud being adapted to engage the free end of the movable contact spring forming part of the respective cooperating make contact group and the surface of each tooth controlling a break contact group which is turned in the direction of said sliding on operation of the said stud being adapted to engage the free ends of the movable contact spring forming part of the respective cooperating break contact group.
2. A contact spring assembly according to claim 1, in which said movable contact springs are slotted at their free ends to form twin contacts and said operating stud member has the shape of a flat strip provided with teeth arranged in pairs opposite to each other, said operating member extending through the slots of the movable contact springs and having its teeth projecting perpendicularly to the longitudinal axis of the movable contact springs and in engageable relation with the latter.
3. A contact spring assembly according to claim 1, said assembly including a transfer contact group, said transfer contact group comprising a stationary contact member and two movable contact springs disposed on opposite sides of said stationary contact member, each of said movable contact members being so pretensioned as to tend to flex its free end into engagement with said stationary contact member, said movable contact members being further so disposed with respect to each other to be selectively releasable to engage said stationary contact member by engagement with opposed surfaces on two adjacent teeth of said comb-like stud member.

4. A contact spring assembly which is made of standardized components permitting maximum variation in switching contact arrangements with a minimum number of standardized parts, comprising: a base means and a plurality of non-conducting spacer members supported thereon in piled-up relation; a plurality of relatively fixed contact elements, one each supported between a pair of adjacent spacer members; a plurality of relatively movable resilient contact elements supported between a pair of adjacent spacers, with each of said movable and fixed contact elements being mounted between a different set of spacers in similar piled-up relation, each movable element cooperating with one of said fixed elements and forming at least one make contact set and one break contact set; each of said movable contact elements being biased towards its cooperating fixed contact element so as to normally make contact therewith; a comb-like operating stud member having substantially evenly spaced teeth thereon with at least one tooth disposed between each pair of adjacent contact elements, each of said teeth having two opposed spaced operating surfaces adapted to engage and operate a movable contact element, and one of said surfaces engageable with one of said movable contact elements to displace it from its cooperating fixed contact element in a direction opposite to normal bias of the movable element.

5. A contact spring assembly as defined in claim 4, further comprising a supporting stud having notches with the same spacing as the teeth on the operating stud, said notches receiving and holding the fixed contact leaves at some distance from their contact ends.

6. A contact spring assembly which is made of standardized components permitting maximum variation in switching contact arrangement with a minimum number of standardized parts, comprising: a base means and a plurality of non-conducting spacer members of substantially uniform thickness supported thereon in piled-up relation; a plurality of relatively fixed contact

- leaf springs, each supported adjacent one end thereof between a pair of adjacent spacer members; a plurality of relatively resilient movable contact leaf springs, one each cooperating with one of said fixed springs and supported adjacent one end thereof between a pair of adjacent spacers, each of said movable and fixed contact springs being mounted between a different set of spacers in similar piled-up relation; each of said movable contact springs being biased towards its cooperating fixed contact spring so as to normally make contact therewith; a comb-like operating stud member having substantially evenly spaced teeth thereon with at least one tooth disposed between each pair of adjacent contact springs, each of said teeth having two opposed spaced operating surfaces adapted to engage and operate a movable contact spring, and one of said surfaces engageable with one of said movable contact springs to displace it from its cooperating fixed contact spring in a direction opposite to its direction of normal bias.
7. A contact spring assembly as defined in claim 6, further comprising a supporting stud having notches with the same spacing as the teeth on the operating stud, said notches receiving and holding the fixed contact leaves at some distance from their contact ends.
